UNITED STATES PATENT OFFICE

144,431

DESIGN FOR A BARBECUE

Hyrum M. Talley, Alhambra, Calif.

Application September 10, 1945, Serial No. 121,977

Term of patent 14 years

(Cl. D81—10)

To all whom it may concern:

Be it known that I, Hyrum M. Talley, a citizen of the United States, residing at Alhambra, in the county of Los Angeles and State of California, have invented a new, original, and ornamental Design for Barbecue, of which the following is a specification, reference being had to the accompanying drawings, forming part thereof.

Figure 1 is a front view in elevation of the barbecue embodying my new design; Fig. 2 is a view in end elevation of the same; Fig. 3 is a top plan view of the same; and Fig. 4 is a perspective view of the barbecue the cover being illustrated in open position.

I claim:

The ornamental design for a barbecue, as shown.

HYRUM M. TALLEY.
